VISBREAKING OF HEAVY HYDROCARBONACEOUS MATERIALS

Wilfred O. Taff and John Weikart, Cranford, and Richard W. Eustis, Fanwood, N. J., assignors to Standard Oil Development Company, a corporation of Delaware

Application December 28, 1950, Serial No. 203,112

5 Claims. (Cl. 196—50)

The present invention relates to a method of treating hydrocarbons. More specifically, the invention pertains to an improved process of reducing the viscosity of heavy hydrocarbon residues of the type of topped or reduced crude or similar materials by a thermal treatment suitable to produce increased proportions of motor fuel range hydrocarbons and fuel oils of improved quality. In its broadest aspect, the invention provides for subjecting heavy residues of the type specified to a viscosity-reducing or "visbreaking" treatment at high temperatures and elevated pressures suitable for the production of higher yields of gasoline and flash-distilling the visbroken product under conditions adapted to maintain the residence time and the temperature of the flash distillation bottoms in the flash distillation zone at desirable minimum values to produce a low sediment fuel oil.

In refining crude oil the first step is normally a simple distillation or "topping" to produce distillate fractions and a heavy residue. In order to obtain maximum yields of high quality motor fuels, all fractions boiling above the gasoline range and particularly those boiling above the heating oil range must be subjected to catalytic cracking. However, the heavy residuum of conventional crude distillation boiling above about 800° F. does not, as such, represent a feed stock suitable for catalytic cracking. Among the methods developed to produce satisfactory catalytic cracking feed stocks from these residues; viscosity reduction or "visbreaking" is one of the most widely used.

Visbreaking involves a treatment of reduced crude or the like at temperatures of about 780°—950° F. and pressures of about 200—1500 p. s. i. g. at feed rates of 1—75 volumes per hour of oil at 60° F. per cracking volume above 750° F. to produce by a mild type of thermal cracking about 5—15 vol. per cent of gas oil, about 5—15 vol. per cent of gasoline and about 85—70 vol. per cent of heavy fuel oil. Specific conditions within the ranges specified depend on the type of the visbreaker feed. The gas oil so formed represents a feed stock suitable for the production of additional amounts of high quality gasoline by catalytic cracking or, after suitable finishing, an acceptable distillate fuel. Of the products formed in visbreaking, the gasoline has the highest and the fuel oil the lowest value. In order to obtain the greatest product realization it is highly desirable, therefore, to reduce the fuel oil yields to a minimum while simultaneously increasing the gasoline and gas oil yields to a maximum. This may be accomplished by increasing the severity of the thermal cracking treatment, that is, by raising the temperature and/or extending the cracking time. However, when so operating the quality of the product fuel oil, particularly its sedimentation characteristics are impaired to an extent which makes the fuel oil unacceptable for most purposes. Therefore, a visbreaking operation permitting the production of increased yields of gasoline and gas oil and simultaneously of fuel oil in smaller amounts but of satisfactory sediment characteristics, has become a need strongly felt in the art of petroleum refining. The present invention provides an operation of this type.

It is, therefore, the principal object of this invention to provide improved means for visbreaking heavy petroleum residues of the type specified, permitting the production of maximum yields of motor and distillate fuels and relatively small yields of a high quality heavy fuel oil. Other objects and advantages will appear from the subsequent description of the invention wherein ref-

2.

erence will be made to the accompanying drawing, the single figure of which is a semi-diagrammatical illustration of a system suitable to carry out a preferred embodiment of the invention.

It has now been found that the thermal cracking severity of the visbreaking operation may be substantially increased without detrimentally affecting fuel oil quality by substantially reducing the temperature and residence time of the visbreaker tar in the zone in which it is separated from lighter visbreaker products. Tar temperatures of about 400°—600° F. and tar residence times of about 20—300 seconds at this point are particularly beneficial, minimum temperatures and residence times being preferred within the ranges specified. These conditions may be maintained in accordance with the invention by a combination of three steps, namely (1) quenching the effluent of the visbreaking zone from visbreaking temperatures of about 780°—950° F. depending on the type of feed to a temperature of about 500°—800° F. prior to pressure release; (2) subjecting the quenched effluent to flash distillation by injecting it into a flash distillation zone at a pressure of about 50—300 p. s. i. g. and steam stripping the light ends from the tar in the flash distillation zone; and (3) further quenching the tar in the bottom of the flash distillation zone to a temperature of about 400°—600° F. while limiting the tar residence time in the flash tower bottom to a substantially constant minimum by suitable overflow means. Particularly the third step has been found to be critical for the purposes of the invention. When operating in this manner, the gasoline yield obtained in the visbreaking process itself may be increased by about 2—10% on feed and the gas oil yield by about the same range with a simultaneous reduction in fuel oil production by about 4—20% on feed of high quality low sediment fuel oil. An increase in the gasoline yield of 2—10% on feed may represent, depending on the type of feed, a 20—100% increase in gasoline yield. Visbreaking conditions suitable for this purpose include temperatures of about 780°—950° F., pressures of about 200—1500 p. s. i. g. and visbreaker feed rates of 1—75 volumes per hour of oil at 60° F. per cracking volume above 750° F. As in conventional operation, specific conditions vary with the type of visbreaker feed. However, quite generally the conditions to be applied in the case of the invention are more severe than those of conventional operation, within the ranges specified. Particularly, the temperature may be about 20°—50° F. higher than that conventionally used for the same feed, so as to increase severity.

While the invention is applicable to all types of conventional visbreaking systems, a visbreaking zone in the form of an extended, narrowly confined path such as a suitable furnace coil excluding excessive soaking times of the visbroken product at substantially visbreaking conditions offers maximum improvement over previous types of operations, when incorporated into the process of the invention. The tube and tank type arrangement providing extensive soaking space for the feed at visbreaking conditions affords definitely less significant improvements.

Having set forth its objects and general nature, the invention will be best understood from the more detailed description hereinafter read with reference to the drawing. The system illustrated in the drawing essentially comprises a visbreaking coil 7 arranged in furnace 9 and a flash tower 15 provided with a tar pot 21 and a tar pot quench circuit 29, 33, 35. The functions and coaction of these elements will be presently described in connection with the treatment of virgin residues from atmospheric crude distillation. It should be understood, however, that the system may be employed in a substantially analogous manner for the visbreaking of other heavy hydrocarbonaceous residues.

In operation, a virgin crude distillation residuum boiling above about 800° F. may be supplied from line 1 by feed pump 3 via line 5 to visbreaking coil 7 substantially at the temperature at which it is recovered from the crude still, say at about 500°—750° F. Coil 7 is arranged in furnace 9 in such a manner as to provide a preheating section maintained at about 700°—850° F., a heating sec-

3

tion maintained at about 780°-950° F. and a relatively short soaking section maintained substantially at the temperature of the heating section. The feed is heated in coil 7 to the temperatures mentioned in the order indicated at a pressure of about 100-1500 p. s. i. g. Coil dimensions and oil feed rate are so correlated that the oil residence time at visbreaking temperatures exceeding 750° F. will be about 0.8-30 minutes, corresponding to an oil throughput of about 75-2 volumes of liquid oil per volume of visbreaking coil per hour (v./v./hr.).

The visbroken product is withdrawn at visbreaking pressure and a temperature of about 780°-950° F. in mixed vapor-liquid phase via line 11 wherein it is preferably quenched to a temperature of about 500°-800° F. by the addition of product tar from line 13. For this purpose about 0.5-1.5 liquid volumes of product tar per liquid volume of residuum feed may be supplied through line 13 at a temperature of about 400°-650° F. as will appear more clearly hereinafter. The quenched product is flashed by means of pressure release valve 14 into a lower portion of the baffled section of flash tower 15 at a temperature of about 450°-800° F. and a pressure of about 100-200 p. s. i. g. Stripping steam is admitted to flash tower 15 via lines 17 at a point below the feed point of line 11 to aid in the removal of distillate products including gasoline and gas oil which leave tower 15 overhead through line 19 to be further worked up in conventional fractionation and catalytic cracking equipment, not shown.

Heavy tar of a boiling range suitable for inclusion in heavy fuel oil is collected in tar pot 21 and handled therein as follows. Product tar is withdrawn via line 23 and passed to storage at a rate of about 0.65-0.95 liquid volumes per liquid volume of residuum feed, controlled by valve 25 which is operated by conventional level control means 27 such as conventional ball float or differential pressure controllers. The tar level in tar pot 21 is so adjusted that a substantially constant tar hold up and a tar residence time of about 0.5-5 minutes, preferably closely approaching the lower limit, is provided at the

similar temperature distribution. Other modifications within the spirit of the invention will appear to those skilled in the art.

The advantages afforded by the present invention will be further illustrated by the following comparative experimental data. Two different crude residua were treated in a pilot plant designed and operated substantially as described above with reference to the drawing. These feed stocks had the following inspections.

10

Table I

25 The tar recovered from the tar pot in each case was blended to a constant Saybolt Furol viscosity of 175 seconds at 122° F. with the same gas oil range flux stock in accordance with accepted conventional practice. These fuel oil blends were then tested for their sediment characteristics by the same filtration procedure at the same conditions and the sediment removed was reported as weight percent. Fuel oil blends indicating sediments in excess of 5% are considered unsatisfactory from sedimentation characteristics.

30 35 The visbreaking experiments were carried out at a visbreaking coil pressure of 350 p. s. i. g., a throughput of 15 v./v./hr. in the visbreaking coil section maintained above 750° F. and a flash tower pressure of about 100 p. s. i. g. Other reaction conditions and the results obtained using residuum A are tabulated below.

residuum feed rates here specified. A stream of tar is circulated from the bottom of tar pot 21 via line 29 by means of pump 31 through a cooler 33 and via line 35 back into the tar pot 21 at a point above the withdrawal point of the circulating tar stream. The temperature of cooler 33 and the tar circulation rate through line 35 are so adjusted that the tar pot temperature is maintained at about 400°-650° F. This may be accomplished by circulating about 0.25-5 liquid volumes of tar per liquid volume of product tar through line 35 at a temperature of about 200°-450° F. A third tar stream may be withdrawn from tar pot 21 and passed through line 13 to line 11 to serve as the quenching medium in line 11 as described above.

The system of the drawing permits of various modifications. For example, the quench could be added at the flash zone rather than in the transfer line to provide

55 60 Comparison of runs F and G indicates that run G which employed the lower tar pot temperature, 603° vs. 794° F., and shorter time, 1 vs. 19 minutes, produced a fuel oil of satisfactory sedimentation characteristics while run F with high temperature and long time conditions in the tar pot produced an unsatisfactory product. It has been previously stated that increased cracking severity degrades fuel oil quality as to sediment but this does not qualify the results above since cracking severity as measured conventionally by gasoline yield is constant. In order to obtain a satisfactory fuel oil without using the process of the invention, the cracking severity and conversion must be reduced and hence gasoline yields will be reduced and heavy fuel oil yield increased.

65 Another example in which a residuum of different character was used at the operating condition previously cited is summarized in Table III below for residuum B.

¹ Too high to be determined using this test procedure. Experiments indicate that this value is in the range of 1-2%.

It will be noted that in run R under conditions of low temperature and short time in the tar pot, the fuel oil showed satisfactory sedimentation characteristics while the high temperature, long time conditions of run Q produced an unsatisfactory fuel oil.

In connection with the experiments reported in Table II and Table III it was also noted that the use of a relatively aromatic flux oil affords a further improvement in the sediment characteristics of tar-fuel oil blends as compared with the use of a relatively paraffinic flux oil. For example, in the case of run Q the sediment could be reduced from an estimated 1-2% to 0.3% by the use of a more aromatic flux having a diesel index of 10 as compared to a relatively paraffinic flux having a diesel index of 40. The significance of this difference resides in the fact that the visbreaking severity may be further increased to produce even higher gasoline yields while still maintaining the sediment characteristics of the final fuel oil blend within desirable limits when using a relatively aromatic gas oil range flux oil to prepare fuel oil blends having a Saybolt Furol viscosity of about 125-175 seconds and otherwise operating in accordance with the invention. The production of fuel oils in this manner is, therefore, a preferred embodiment of the present invention.

It has also been found that desalted residua are superior feed stocks for the purposes of the invention particularly with respect to coil operability as compared to straight residua. Desalted feed stocks have been found to produce coke amounting to about 24% of the volume of the visbreaking coil in 16 hours as compared to 56% of this volume within 12 hours in the case of straight residua. It is preferred, therefore, to subject the feed stocks or preferably the original crude oil to a suitable conventional desalting treatment, such as a water wash followed by an emulsion breaking procedure, to permit realization of the maximum advantage in connection with the invention when applied to coil-only operation, as compared to tube-and-tank procedures.

The foregoing description and exemplary operations have served to illustrate specific embodiments of the invention but are not intended to be limiting in scope.

What is claimed is:

1. In the process of viscosity breaking heavy hydrocarbonaceous residues by a thermal treatment carried out at temperatures of about 780°-950° F., pressures of about 200-1500 p. s. i. g. and treating times corresponding to feed rates of about 1-75 volumes per hour of feed of 60° F. per volume of reactor space above 750° F. to produce a visbroken material and separating tar and distillate fractions including gasoline from said material, the improvement which comprises carrying out said treat-

ment at severe conditions of temperature, pressure and treating times within the ranges specified, conducive to the production of relatively large amounts of gasoline and relatively small amounts of tar, said treatment conditions being such as to initiate degradation of the tar fraction to produce an intolerable proportion of sediment if the temperature were maintained for a substantial period of time after leaving the reactor, quenching said visbroken material after leaving the reactor and before substantial pressure reduction to reduce its temperature about 150° to 280° F., flashing said material at said reduced temperature into a flashing zone maintained at a pressure below said severe visbreaking pressure, stripping distillate fractions off said flashed material with steam in said flashing zone, collecting tar in a zone below said flashing zone, maintaining said tar in said collecting zone at a temperature of about 400°-600° F. but below said flashing temperature and for a residence time of about 0.5-5 minutes, maintaining said collecting zone temperature by circulating tar from said collecting zone through a cooling zone and back to said collecting zone, withdrawing tar from said collecting zone at a rate adequate to limit the tar residence time to that specified, and withdrawing distillate fractions from said flashing zone.

2. The process of claim 1 in which said material is quenched to a temperature of about 500°-800° F. prior to flashing, by the addition of tar withdrawn from said collecting zone.

3. The process of claim 1 in which said hydrocarbonaceous residues are desalted prior to said visbreaking treatment, said visbreaking treatment being carried out in an extended narrowly confined visbreaking zone externally heated to said severe visbreaking temperatures.

4. The process of claim 1 in which said withdrawn tar is blended with an aromatic type of flux oil to produce a heavy fuel oil.

5. The process of claim 1 in which said collecting zone temperature and residence times are maintained within the lower brackets of the ranges specified.
